HIS ATTORNEY.

UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

ROCK DRILL.

Application filed July 10, 1925. Serial No. 42,646.

This invention relates to rock drills, but more particularly to a fluid actuated rock drill of the hammer type in which the inlet and compression relief are controlled by independent valves, the main free exhaust being controlled by the piston.

The objects of the invention are to enable the fluid actuated inlet and compression relief valves to be conveniently located rearwardly of the cylinder in the back head parts of the machine with the compression relief valve between the inlet valve and the cylinder.

Another object of the invention is to enable such construction to be carried out without materially lengthening the machine.

The invention is shown in one of its preferred forms in the accompanying drawings, in which—

20. Figure 1 is a longitudinal sectional elevation of so much of a rock drill as will serve to illustrate the invention,

Figure 2 is a similar view taken on a section at right angles to the section on which

25. Figure 1 is taken, and

Figure 3 is a transverse view partly in section taken on the line 3—3 of Figure 2 looking in the direction of the arrows.

Referring to the drawings, the cylinder A 30 having the free exhaust port B located centrally thereof is provided with the piston C controlling said exhaust port. The front head D, the back cylinder washer E, the head block F and the back head G are held 35 together by the usual side bolts H. The shank J of the drill steel projects into the front head in position to be struck by the shank K of the hammer.

The supply of pressure fluid to the machine is controlled by a suitable throttle valve L conveniently located in the back head and the inlet to both ends of the cylinder is controlled by the fluid actuated inlet valve O in the valve box P located in the 45 back head G rearwardly of the cylinder. The valve box P is formed with a rectangular chamber Q and is provided with a cover plate R having the inlet opening S communicating with the inlet passage T in the 50 back head.

The valve O is in the form of a rectangular hollow block bodily slidably longitudinally in the rectangular chamber Q of the valve box P and this valve is constructed substantially like the valve disclosed in my copend-

ing application, Serial No. 31,485, filed May 20, 1925, in which the details of construction are covered.

Pressure fluid entering through the inlet passage T passes over one end of the valve as shown in Figure 1 through the port U in the valve box, thence through the ports V and W in the head block and cylinder washer, and thence through the port X to the rearward end of the cylinder for driving the piston forward. After the piston has uncovered the exhaust port B, the pressure on the face Y of the valve O is reduced and pressure fluid under compression acting against the face Z of the valve causes the valve to move to its opposite position, thus admitting fluid over the face Z of the valve through the passage a in the valve box and through the ports b and c in the head block and cylinder washer and the passage d in the cylinder to the inlet port e at the forward end of the cylinder to drive the piston rearwardly from which point the cycle is repeated.

The compression relief valve f is in the form of an oscillating plate distributing from the center towards both ends and located between the inlet valve O and the cylinder, in the cylinder washer E. The valve f oscillates on a pin g and controls exhaust ports h and j conveniently located in the head block F. The port c in the back cylinder washer E as shown in Figure 3 extends underneath one end k of the valve f so that as the piston moves forwardly, the compression in the forward end of the cylinder is relieved through the port e, passage d, port c and thence over the end k of the valve f to the relief port h as indicated in Figure 2. The relief valve f is maintained in the position indicated in Figure 2 during the forward stroke of the piston, due to live pressure fluid through the port p leading to the rearward end of the cylinder. On the return rearward stroke of the piston, live pressure holds the end k of the relief valve f closed and compression is relieved through the port p and over the end q of the relief valve to the exhaust port j.

I claim:

1. In a fluid actuated rock drill, the combination of a cylinder and reciprocating piston, a free exhaust port located centrally of the cylinder and controlled by the piston, a valve box having a rectangular chamber lo-

105

110

cated rearwardly of the cylinder, a compression actuated inlet valve in the form of a rectangular hollow block bodily slideable longitudinally in said valve box, inlet ports 5 for the ends of the cylinder controlled only by said inlet valve, and a compression actuated compression relief valve in the form of a thin flat oscillating plate located between the said inlet valve and the cylinder.

2. In a fluid actuated rock drill, the combination of a cylinder and reciprocating piston, a free exhaust port located centrally of the cylinder and controlled by the piston, a valve box having a rectangular chamber located rearwardly of the cylinder, a compres-

sion actuated inlet valve in the form of a rectangular hollow block slideable longitudinally in said valve box, inlet ports for the ends of the cylinder controlled only by said inlet valve, and a compression actuated compression relief valve in the form of a thin, flat oscillating plate, tapering from the center towards each end and located between the inlet valve and the cylinder with its axis of oscillation at right angles to the longitudinal axis of the rock drill. 20 25

In testimony whereof I have signed this specification.

CHARLES C. HANSEN.
